UNITED STATES PATENT OFFICE

2,503,166

SHOE MACHINE

Alfred R. Morrill, deceased, late of Woodstock, Vt., by Ruth W. Morrill, administratrix, Woodstock, Vt., assignor to United Shoe Machinery Corporation, Flemington, N. J., a corporation of New Jersey

Application March 12, 1947, Serial No. 734,158

22 Claims. (Cl. 12—17)

1

The present invention relates to machines for the manufacture of shoes, and more particularly to improvements in the shoe supporting, shoe feeding and shoe controlling means of automatic machines of the general type illustrated in the patents to Morrill No. 2,359,664, dated October 3, 1944, and No. 2,323,346, dated July 6, 1943.

In machines of the general type referred to, and as shown in the appended drawings, an automatic shoe support is provided which takes the form of a jack adapted to receive and to hold a lasted shoe, and a supporting structure on which the jack is mounted for turning, tipping and feeding movements in order to present the shoe properly to the operating devices and to transfer the operation about the sole margin of the shoe. The operating connections for the jack include a pattern cam shaft driven in timed relation to the shoe operating devices and having mounted thereon pattern cams for imparting said positioning movements to the jack. The pattern cam shaft and cams thereon are adapted and arranged to be driven through one revolution for each complete operation about the shoe. The pattern cams operate during this period to impart the required positioning movements to the jacked shoe to transfer the operation about the sole margin of the shoe, and thereafter when the shoe is disconnected from the operating devices, to re-establish the jacked shoe in the initial loading position away from the operating devices and with the toe of the shoe pointing to the right.

It is one object of the invention to provide a novel and improved means for adapting the drive for the pattern cam shaft to different conditions of operation of the automatic machine on which operations of different length are performed about the sole margin of the shoe as, for example, when a change is made from an operation extending from the breast line of the heel about the forepart of the shoe only, to an operation which extends also about the heel seat, passing entirely around the sole margin of the shoe.

Specifically, it is an object of the invention to adapt the operation of the automatic shoe support including the jack and the supporting and actuating mechanism for the jack to transfer the operation entirely around the sole margin of the shoe including the heel seat in timed relation to maintain the desired rate of feed of the shoe with relation to the mechanism for operating upon the shoe, and thereafter to return the jack and associated operating parts to an initial loading position.

It is another object of the invention to provide

2

a novel and improved construction and arrangement of the supporting and actuating mechanism for the jack which is particularly adapted for use under conditions in which the operation has been transferred entirely around the shoe including the heel seat to permit the return of the jacked shoe and of the automatic supporting and actuating mechanisms therefor to the initial starting position away from the shoe operating devices quickly and with a minimum amount of movement of the several cooperating mechanisms including the jack.

With these and other objects in view as may hereinafter appear, the several features of the invention consist in the devices, combinations and arrangement of parts hereinafter described and claimed which together with the advantages to be obtained thereby will be readily understood by one skilled in the art from the following description taken in connection with the accompanying drawings, in which Fig. 1 is a view in right side elevation of an automatic inseam shoe sewing machine embodying in a preferred form the several features of the invention, portions of the casing having been broken away to show the supporting structure and actuating mechanism for the shoe supporting jack; Fig. 2 is a fragmentary detail view on an enlarged scale and partly in section of a portion of the pattern shaft drive shown in Fig. 1, illustrating particularly the change speed driving connections for the pattern shaft provided in accordance with the invention; Fig. 3 is a fragmentary plan view on a large scale showing a portion of the drive to the pattern cam shaft, the jack, feed, pitch, roll and turn cams for 360 degrees of rotation of the jack and return, the associated follower levers, and the manual control for the change speed connections illustrated in Fig. 2; Fig. 4 is a sectional plan view of the pattern cam shaft, the pattern cams as shown in Fig. 3 for effecting a 360 degree rotation of the jack, and the supporting structure for the jack; Fig. 5 is a detail sectional view in elevation taken on the line 5—5 of Fig. 4 illustrating particularly the rotary wheel, supporting bearings and gimbals on which the jack spindle is mounted, to turn together with the mechanism for latching the jack to turn with the jack turning connection and for disconnecting the jack therefrom; Fig. 6 is a fragmentary sectional view of the latching mechanism corresponding with a portion of Fig. 5, but with the jack disconnected from the rotary wheel and locked against movement while the wheel is rotated to the initial starting position; Fig. 7 is a detail sectional plan view on

an enlarged scale of the pattern cam shaft, pattern levers, and a set of jack, feed, pitch, roll and turn cams adapted for controlling the operation of the jack to transfer the operation from the breast line of the heel about the forepart of the shoe only; Fig. 8 is a fragmentary sectional view of the cam lever supporting shaft shown in Fig. 7, but rocked to move the cam levers away from their cams; Fig. 9 is a detail view in right side elevation illustrating particularly the pattern cam levers and their connections with the jack supporting and controlling mechanisms; and Fig. 10 is a fragmentary detail view in front elevation of the foot treadle for moving the pattern cam levers away from their cams.

Referring specifically to the drawings, the automatic shoe machine disclosed particularly in Fig. 1, comprises a casing or frame built up of several sections including a floor section 10 housing particularly an oil sump and the various foot treadle controls, a middle section 12 housing principally the jack supporting mechanism and the pattern mechanism of the machine, a head section 14 housing the shoe operating mechanism illustrated in the Morrill Patent No. 2,359,664 above referred to, and the top section 16 supporting thereon the driving motor 18, reduction driving gears therefrom and a distributing reservoir forming part of the oiling system for the machine.

As indicated in dotted lines in Fig. 1, the drive is taken from the motor 18 directly downwardly through the head section 14 of the casing to a stop motion including the main driving and stopping clutch for the machine, and thence to the sewing cam shaft by means of which the sewing mechanism is driven and to the pattern cam shaft which controls the automatic operation of the jack.

In automatic machines of the general type here disclosed, the rate of drive of the pattern cam shaft is adjusted with relation to the predetermined or set rate of feed of the shoe operating mechanism about the sole margin of the shoe to cause the pattern mechanism, including the pattern cam shaft and cams, to be rotated through substantially a complete revolution during the same period in which the shoe operating mechanism is caused to complete the operation about the shoe sole. The inseam shoe sewing operation referred to, ordinarily starts at the breast line of the heel, passes around the forepart of the shoe, and terminates when the breast line of the heel is again reached.

In accordance with the present invention, the pattern mechanism of the machine including the driving connections thereto, are particularly constructed and arranged to permit an alternative adjustment of the machine for the performance of operations which extend from the breastline of the heel around the forepart of the shoe only and for the performance of operations which extend additionally around the heel, passing entirely around the sole margin of the shoe.

A feature of applicant's novel construction consists in the provision of two alternatively available sets of pattern cams on the cam shaft for controlling the operation of the jack during the performance of these alternative operations about the sole margin of the shoe. Another feature of applicant's construction consists in the provision of means for controlling the rate of drive of the pattern cam shaft relative to the rate of drive of the shoe operating mechanism in order to maintain the same rate of feed of the sole margin of the shoe past the shoe operating mechanism un-

der each of the operating conditions above referred to in which the operation is transferred from the breast line of the heel about the forepart of the shoe only, or alternatively, is transferred entirely around the sole margin of the shoe including the heel seat. The mechanism provided in accordance with the invention for varying the rate of drive, comprises a group of change speed gears including a change speed gear unit shiftable to cause the pattern cam shaft to be driven at either of two alternative driving rates.

As shown in the drawings, the driving connections for the machine include a reduction gear 20 on the armature shaft 22 of the motor 18, and a reduction gear 24 which is connected to drive the main drive shaft 26. The shaft 26 is in turn connected by means of gears 28, 30 to drive an external coned clutch member 32 forming the driving element of the main driving clutch which is loosely supported to turn on a vertically arranged drive shaft 34. The cooperating driven element of the main driving and stopping clutch comprises an internal coned clutch member 40 keyed to turn with and to slide on the drive shaft 34. The driven member 40 of the clutch is connected through the vertical drive shaft 34 to drive the pattern mechanism of the machine including the pattern cam shaft 42, and is also connected to drive the sewing cam shaft 44 through the meshing engagement of a spiral gear 46 formed on the upper periphery of the driven clutch member 40 with a spiral gear 48 secured to the sewing cam shaft 44. The drive to the pattern cam shaft is taken from the main clutch downwardly through the drive shaft 34 and clutch 50 as generally indicated in Fig. 1, and thence through an aligned shaft 52 to a variable speed drive device generally designated at 54 in Fig. 2, by means of which the rate of drive of the pattern cam shaft is adjusted in accordance with the size of shoe being operated upon to maintain a constant rate of feed of the sole margin past the shoe operating mechanism.

In accordance with the invention, the pattern cam shaft is arranged to be driven from the driven shaft of the variable speed mechanism through a change speed gear unit which is shiftable to drive the cam shaft at either of two rates, one rate being set for the transfer of the operation upon the sole margin of the shoe from the breast line of the heel about the toe portion of the shoe only, and the other being set for the transfer of the operation entirely around the shoe including the heel seat. The change speed mechanism referred to comprises a change speed gear unit consisting of gears 58, 60 splined to the lower end of shaft 52 and arranged for axial shifting movement in one direction to cause the gear 58 to be brought into mesh with a driven gear 62 for use during the operation about the forepart of the shoe only, and for shifting movement in the opposite direction to engage the gear 60 with gear 64 when the operation is to be transferred entirely around the shoe including the heel seat. The gears 62, 64 are mounted upon a stub shaft 66 to turn as a unit with a driving gear 68 which meshes with a large gear 70 on a drive shaft 72. The pattern shaft 42 is arranged to be driven from the drive shaft 72 through gear connections which comprise a series of identical driving gears 74 on the shaft 72, which are arranged for engagement with a driven gear 76 mounted on the upper end of the axially shiftable pattern shaft 42 for any position of adjustment of the pattern shaft.

In accordance with the disclosure of the patent

to Morrill above referred to, the pattern shaft 42 is adjustable vertically in order to render different sets of jack actuating cams selectively operable to control the operation of the jack. As best shown in Fig. 1 of the drawings, vertical adjustment of the pattern cam shaft 42 is effected by means of a manually operable lever arm 80 which is supported to turn on a stationary pivot 81, and has formed on the hub portion thereof, an internal gear 82 meshing with a pinion 83 on a transversely extending shaft 84. A pinion 85 on the shaft 84 meshes with a circular rack 86 formed on the upper portion of a pattern cam lifting shaft 87 axially disposed within an axial bore in the pattern shaft 42. The manually operable lever arm 80 is provided at its outer end with a control handle (not shown) having a spring-pressed detent for engagement with recesses 89 corresponding with each of the vertically adjusted positions of the pattern cam shaft 42.

The mechanism for controlling the rate of rotation of the pattern cam shaft with relation to the rate of operation of the sewing mechanism for transferring the operation alternatively about the forepart and heel seat, or about the forepart only of the shoe, comprises the vertically shiftable change speed gears 58, 60. Movement of these gears upwardly so that the gear 58 meshes with the driven gear 62 will cause the pattern shaft to be driven at a relatively faster rate, normal for operations in which the sewing or other operation is carried from the breast line of the heel around the forepart of the shoe only. Downward movement of the change speed gears 58, 60 so that the relatively smaller gear 60 is in mesh with the gear 64, will cause the pattern shaft to be driven at a relatively slower rate to allow time for the continuance of the operation around the entire sole margin of the shoe.

Shifting of the pattern shaft change speed mechanism from one to another position is effected by means of a manual control lever 90 (see Figs. 1, 2 and 3) mounted at the right side of the machine on the outer end of the rock shaft 91 carried in a bearing 92 in the machine frame. At its rear end the shaft 91 carries a lever arm 94 with a gear shifting shoe 96 pivotally mounted thereon for engagement in an annular groove 98 provided between the gears 58, 60. The hand lever 90 as best shown in Fig. 3, is provided with a knurled knob 102 and a spring-pressed detent plunger 104 controlled thereby which is adapted for engagement in any one of three recesses 106 formed in a face plate 108 for positioning the hand lever 90 and change speed gears 58, 60 in either of two alternate operating positions or in the intermediate neutral position shown in Fig. 2.

The jack shown with the illustrated embodiment of the invention, is that shown in the Morrill Patent No. 2,323,346 above referred to, which is particularly constructed and arranged to be rotated where so desired through more than 360 degrees of rotation. The jack as generally indicated in Figs. 1 and 4 of the drawings, comprises a shoe supporting and clamping unit 112 which is rigidly supported at its toe end on the upper end of a jack spindle 114. The jack is connected with a feed lever 116 by means of a feed link 118 which has a swivel connection 120 with the toe end of the jack and is constructed and arranged to lie wholly below the level of the shoe supporting and clamping unit 112 to permit complete freedom of rotation of the jack.

The supporting structure for the jack is similar to that of the Morrill Patent No. 2,359,664 above

referred to, except for such changes as will be hereinafter more fully pointed out. The lever supports for the jack as indicated in Fig. 4, include a horizontal supporting arm 124, in the forward end of which the lower end of the jack spindle 114 is mounted to rotate and to swing freely on a universal joint, a pitch support lever 126 on which the arm 124 is mounted to swing vertically, and a roll support lever or frame 128 pivotally mounted at its lower end in the machine base so as to be capable of swinging about a horizontal axis, and upon which the support 126 is mounted so as to swing about a substantially vertical axis.

The operating connections provided for controlling the operation of the several lever supports referred to, include a feed cam lever 130, a turn cam lever 132, a roll cam lever 134 and a pitch cam lever 136 loosely mounted one above the other to turn on a vertically arranged pivot shaft 138 (see Figs. 4, 7 and 8). These levers are adapted to cooperate with corresponding sets of cams on the pattern cam shaft 42, which in the illustrated form of the invention include two alternatively available sets, one for controlling the jack during an operation which extends from the breast line of the heel around the forepart of the shoe only, and the other for use in the operation which extends entirely around the sole margin of the shoe including the heel seat. A series of cams for use in transferring the operation entirely around the sole margin of the shoe including the forepart and heel seat are shown in Figs. 2, 3 and 4 of the drawings. These cams include a feed cam 140, a turn cam 142, a roll cam 144 and a pitch cam 146. Fig. 7 discloses the outlines of the alternatively available series of cams for controlling the jack during an operation around the forepart of the shoe only, and include a feed cam 148, a turn cam 150, a roll cam 152 and a pitch cam 154.

The sets of cams above referred to, are made alternatively available as previously pointed out, by a vertical adjustment in the position of the pattern shaft 42. To hold the cam levers away from the cams while the cam shaft is being adjusted, the shaft 138 on which the cam levers are mounted, is provided with shouldered collars 156 (see Figs. 2, 7, 8 and 9) which are rendered operative by clockwise movement of the shaft 138 to engage with adjustable stop screws 158 on the hubs of the levers, and to move the cam ends of the levers away from the cams as shown particularly in Fig. 8. For rocking the shaft 138, connections are provided (see Figs. 4, 7 and 8) controlled by means of a foot treadle 160 (Figs. 4, 7 and 10) located at the right side of the machine. The foot treadle 160 is supported intermediate its length on a pivot pin 162. At its lower end the treadle lever 160 is connected by means of a pair of links 164 to a slide member 166 extending transversely of the base of the machine, and having a pin and slot connection with a lever arm 168 secured to the lower end of the shaft 138 (see Fig. 7). For the normal running position of the parts, the foot treadle 160 remains in the raised inoperative position shown in Figs. 4, 7 and 10. Movement of the treadle downwardly by the operator acts to straighten the toggle and to shift the slide 166 to the left, so that the pivot shaft 138 is rocked in a clockwise direction to the position of the Fig. 8, to move the levers away from their cams.

The pitch cam lever 136 is connected to impart pitch tipping movements to the jack by means of a link 170 which is connected at one end with

the pitch cam lever 136 and at its other end with the pitch support lever 126. The roll cam lever 134 is connected to impart roll tipping movements to the jack by means of a link 172 which is connected at one end to the roll cam lever 134 and at its other end to the roll support lever 128. The feed cam lever 130 is connected to impart feed movements to the feed lever 116 of the machine through link connections which are arranged to be automatically adjusted in accordance with the size of shoe being operated upon. These connections are not here specifically shown, since these parts have been fully set forth in the Morrill Patent No. 2,359,664 above referred to, and form specifically no part of the present invention.

The mechanism actuated from the turn cam lever 132 for imparting turning movements to the jack as best shown in Figs. 1 and 4, comprises a cone-shaped pulley member 176 having at its upper end a pinion 178 arranged to mesh with a gear segment 180 on the cam lever 132. Rotational movement is imparted to the jack from the pulley member 176 by means of a cord 182 which is secured at one end to a pulley 184 on the lower end of the member 176, and thence passes around an idler pulley 186 on the frame 128, an idler pulley 188 on the support 126, an idler pulley 190 on the jack supporting arm 124, and around a wheel 192 at the outer end of the jack supporting arm 124 on which the jack spindle 114 is mounted for turning movement. Thence the cord extends rearwardly over an idler pulley 194 and downwardly to a weight 186 which serves to maintain an adequate tension on the cord. As shown in Fig. 1, the jack is arranged to be further supported by means of an upwardly extending supporting rod 198 connected at its upper end by means of a universal joint with the under side of the jack supporting arm and at its lower end by means of another universal joint to the forwardly extending arm of a bell-crank lever 200 which is loosely supported to turn on a pivot shaft 202. A pair of heavy tension springs 204 connected to two downwardly extending arms of the lever 200 tend to move the lever 200 and rod 198 upwardly to maintain the jacked shoe yieldably in engagement with the shoe operating mechanism. A tension spring 206 connected between the rod 198 and the downwardly extending tip 208 of the spindle 114 tends to swing the jack and spindle 114 outwardly away from the operating mechanism.

When the machine is stopped, the jack is depressed so that it is permitted to swing outwardly to its inoperative position by means of a toggle connection comprising a toggle link 210 connected to the lever 200 and a cooperating toggle link 212 mounted on a fixed pivot 214. The toggle is straightened to depress the jack through connections which include a control rod 216 provided at its lower end with a washer 218 for engagement with a forward extension of the toggle link 212. The rod 216 is arranged to be moved upwardly during the operation of the machine stop motion to straighten the toggle. Inasmuch as the jack mechanism thus generally referred to, is similar to and operates in a similar manner to that illustrated in the Morrill Patent No. 2,359,664 above referred to, no further description thereof is believed necessary.

In automatic machines of the character described, at the completion of the operation upon the shoe, the jacked shoe is disengaged from and moved away from the shoe operating devices,

and a final increment of movement is imparted to the pattern cam shaft to cause the several parts of the automatic mechanism to be returned to their initial starting position. During this 5 return operation, the mechanism for turning the jack is rotated rapidly in the reverse direction carrying with it the jack which is thus brought to the loading position with the toe facing to the right. Where the operation on the sole margin 10 of the shoe is extended entirely about the shoe sole including the heel seat, the jack turning connections must be operated in the reverse direction a substantially greater distance than is required for the return following an operation 15 from the heel seat around the toe only. Instead of being required to return through approximately one half revolution, the jack supporting wheel 192 and jack mounted thereon must be returned through a full revolution. In order to maintain the necessary operating relationship 20 and timing of this mechanism to the other elements of the automatic support and the turn mechanism including the wheel 192 and jack, it has been found necessary to employ a rate of 25 return movement of the turning mechanism and jack which taken with the increased swing of the jack in the reverse direction has caused objectionable strains to be placed on the mechanism. There is also the further objection that the operator 30 is exposed to the risk of serious injury from contact with the rapidly moving jack and associated parts.

A feature of the present invention consists in the improved construction and arrangement of 35 the supporting and actuating mechanism of the jack to effect the return of the automatic supporting and actuating mechanisms to their initial starting position and the location of the jack in its initial starting position away from 40 the shoe operating devices upon completion of an operation completely about the shoe including the heel seat without the necessity of imparting any rotational movement to the jack beyond that required to establish the jack in the loading position.

In accordance with the invention, the jack is adapted to be operatively disconnected from its supporting wheel 192 and to be turned independently thereof. Referring to Fig. 5 of the 50 drawings, the wheel 192 is mounted to turn on a vertical axis on a ring ball bearing 224, and provides support for a ring member 226 which carries the jack and is rotatable independently of the wheel 192. The ring member 226 is mounted to turn on a recessed annular surface 55 227 formed on the upper surface of the wheel 192, and is held in position by means of a locking ring 228 which is secured to the upper surface of wheel 192 at its outer edge and overlies the outer edge of the ring member 226. The jack is supported to swing freely about its support on the ring member 226 on a universal joint which takes the form of a pivot 230 carried in the ring member 226 and an intersecting pivot 60 232 mounted to extend across a slotted portion 234 of the spindle 114.

Further in accordance with the invention, a latching device is provided which is normally operative to latch the ring member 226 and jack 70 carried thereon to turn with the wheel 192 and is arranged to be shifted automatically to an alternative disengaged locking position upon completion of the operation about the shoe so that the jack is locked against rotational movement while the wheel 192 of the jack mechanism

is permitted to turn through a full revolution in the reverse direction, when the latch will again return to its operative position.

The ring member 226 and jack spindle 114 are connected to turn with the wheel 192 by means of a latch 236 which is carried on the ring member 226 and is arranged for latching engagement with a notch formed in the annular ring 228 secured to the upper side of the wheel 192. The latch 236 is pivotally supported on a pivot pin 240 mounted in a lug 242 on the ring support 226. A tension spring 244 tends to rotate the latch in a clockwise direction to the position shown in Fig. 5, in which the downwardly extending projection thereof bears against the cammed inner edge 246 of the annular ring 228, and is normally pressed into a notch 248 formed in the ring to rigidly secure the ring member 228 to turn as a unit with the wheel 192.

At the completion of the operation upon the shoe, and at that point when the jack and shoe are moved outwardly away from the shoe operating devices, the latch 236 is moved in a counter-clockwise direction from the operating position shown in Fig. 5 to the inoperative jack locking position of Fig. 6, so that the wheel 192 is disconnected from the ring support 226 of the jack, and may be rotated freely in a reverse direction through one entire revolution to its starting position, while at the same time the jack is securely locked in the position taken at the end of the operation upon the shoe. In the position shown in Fig. 6, an upwardly extending portion of the latch 236 is arranged to be engaged in a notch 250 formed in the outer wall of the jack supporting arm 124, while the lower end of the latch 236 rides upon the bevelled inner edge 246 of the annular ring 228 to maintain the latch in its inoperative jack locking position. As the wheel 192 at the completion of the return movement through one revolution is brought again to its initial angular position with relation to the ring support 226 and the jack, the latch 236 is permitted to drop into engagement with the notch 248 in the ring 228, thus again connecting the jack to be turned with the wheel 192.

The latch 236 is arranged to be moved from its operative latching position to the disengaged jack locking position of Fig. 6, by means of a spring-pressed actuating member 254 pivotally mounted on an upwardly extending arm or bracket 256 secured to the outer end of the jack supporting arm 124. The actuating member 254 is normally held in a retracted position to the right as shown in Fig. 5, by means of a leaf spring 258 which bears against a portion of the bracket 256. Outward swinging movement of the spindle 114 to the dotted position of Fig. 5 in moving the jack away from the shoe operating mechanism at the completion of the operation on the shoe, causes the spindle 114 to engage the actuating member 254, moving said member to the dotted position shown in Fig. 5, in which it wipes past and moves the latch 236 against the pressure of spring 244 to the inoperative jack locking position. The wheel 192 immediately starts to rotate in the reverse direction as the cam follower lever 132 rides against the steeply sloped return portion of the jack turn cam 142, causing the lower end of the latch 236 to be engaged against the surface 246 of the annular ring 228. Upon completion of the reverse movement of the jack turn connections including the wheel 192 through a full revolution, the latch 236 held against the cammed surface 246 of the locking ring 228

by its spring 244, again drops into engagement with the notch 248 to re-establish the operating connection between the wheel 192 and jack supporting ring member 226. The jack is finally located in its initial loading position in accordance with the dictation of the several pattern cams including the pattern turn cam 142.

For the performance of an operation entirely around the sole margin of the shoe including the heel seat, the supporting and actuating mechanism for the jack is adjusted and is caused to operate in the following manner:

The cam levers including the feed cam lever 130, the turn cam lever 132, the pitch cam lever 136 and the roll cam lever 134 are forced away from their cams and the bank of pattern cams on the pattern cam shaft is adjusted vertically to cause the proper set of operating cams 140, 142, 144 and 146 to be moved into operating position.

20 The operations which must be performed by the operator to condition the jack actuating devices for the transfer of an operation about the entire shoe or alternatively about the forepart of the shoe only, may be summarized briefly as follows:

Assuming that an operation entirely around the sole margin of the shoe including the heel seat is contemplated, the bank of pattern cams will be moved vertically to bring the feed cam 140, turn cam 142, roll cam 144 and pitch cam 146 into operation relative to the cooperating cam levers to the position shown in Figs. 1, 2 and 3. As shown in these figures, the pattern cam shaft 42 and lifting lever 87 have been moved to their extreme high position. In order to effect this adjustment, the operator first actuates the lever 160 (see Fig. 7) to rock the shaft 138 to the position shown in Fig. 8, thus moving the cam follower levers away from the cam bank. Vertical adjustment of the cams is then effected by actuation of the control lever 80 acting through internal gear 82, pinion 83, rack 86 and cam lifting rod 87. The foot treadle 160 is then released to permit movement of the rock shaft 138 with the cam levers against the pattern cams. The control lever 90 is now set in the extreme down position shown in Fig. 1, so that the gear 60 meshes with the driven gear 64 to drive the cam shaft 42 at the slower rate with relation to the operating mechanism. The machine is now in condition to be started. Following the usual practice in machines of this type, a shoe is placed on the jack which is pressed downwardly or jiggled to release the toggle, and the shoe is brought into operating relation to the operating mechanism in the starting position, thus setting the machine for operating upon a shoe of the size presented in the machine. The operator now steps on the foot treadle to start the machine into operation.

During the following operation about the shoe, the jack is arranged to be rotated on its support by means of the connections controlled from the turn cam 142 including the wheel 192 to which the jack is connected by the engagement of latch 236 in notch 248 in annular ring 228. At the end of the operation which is performed entirely about the shoe, the jack will have been rotated through approximately 360 degrees and is returned angularly to its starting position.

As previously noted, the outward movement of the jack on its spindle 114 to the inoperative position shown in dotted lines in Fig. 5 upon completion of the operation about the shoe, is em-

11

ployed to actuate the actuating member 254 to trip the latch 236 from the operating position of Fig. 5 to the alternative inoperative locking position of Fig. 6, in which the latch 236 engages with the stationary notch 250, the latch being held in this position by the engagement of the tail of the latch with the cammed surface 246 of ring 228 as the wheel 192 carrying with it ring 228 is rotated in the reverse direction. When the wheel 192 and ring 228 have returned to their starting position, the latch 236 acted upon by its spring 244 again drops into engagement with the notch 248.

In the event that it is desired to set up the machine alternatively for operation upon a shoe in which the operation is to be carried from the breast line of the heel about the forepart of the shoe only, the operator first actuates lever 160 to rock shaft 138 and the cam follower levers away from the bank of pattern cams, and then moves the control lever 80 downwardly to bring feed cam 148, turn cam 150, roll cam 152 and pitch cam 154 into operative relation to the follower levers. Control handle 90 is now moved upwardly 180 degrees from the position shown in Fig. 1, to raise driving gears 58, 60 so that the gear 58 meshes with gear 62 to drive the pattern cam shaft 42 at the relatively faster rate with relation to the operating mechanism. For an operation which extends about the forepart of the shoe only in which the jack is rotated approximately 180 degrees, it will be understood that the jack remains coupled at all times to the wheel 192 and is returned therewith in the reverse direction to starting position upon the completion of the operation about the forepart of the shoe.

The invention having been described, what is claimed is:

1. In a machine for operating upon shoes, means for operating along the sole margin of the shoe, a shoe supporting jack, means for moving the jack in accordance with an operating cycle to present a jacked shoe to the operating means and to transfer the operation of said operating means entirely around the sole margin of the shoe including means for imparting tipping and feeding movements to the jack, and a jack rotating wheel adapted to be rotated in one direction from a starting position through one revolution, and thereafter upon completion of said operation in a reverse direction to said starting position, disconnectible means connecting the jack to turn with the wheel, and means to disconnect the jack from the wheel to cause the wheel to be rotated independently of the jack to the starting position.

2. In a machine for operating upon shoes, means for operating along the sole margin of the shoe, a shoe supporting jack, supporting and actuating means adapted for imparting turning, tipping and feeding movements to the jack to present a jacked shoe to the operating means and to transfer the operation entirely around the sole margin of the shoe including a jack rotating wheel arranged to be rotated from a starting position in one direction through a full revolution to complete said operation, and in the reverse direction to return said jack rotating wheel to the starting position, and connecting means shiftable between connecting and disconnected positions arranged to connect the jack to turn with the wheel to transfer the operation about the shoe and shiftable to said disconnected position during the reverse movement of the jack rotating wheel to the starting position.

3. In a machine for operating upon shoes,

12

means for operating along the sole margin of the shoe, a shoe supporting jack, a system of supporting levers on which the jack is mounted for turning, tipping and feeding movements, jack actuating means including a jack rotating wheel arranged to be rotated in one direction to turn the jack to transfer the operation entirely around the sole margin of the shoe and to be returned in the opposite direction to its starting position, 5 and a connecting device shiftable between an operative position connecting the jack to rotate with the wheel and to an alternative disengaged jack locking position in which the jack is locked against rotational movement during the return 10 movement of the jack rotating wheel to the starting position.

4. In a machine for operating upon shoes, means for operating along the sole margin of the shoe, a shoe supporting jack, a jack supporting assembly including a jack supporting arm, a jack rotating wheel mounted to turn thereon, a rotatable jack supporting member concentric with the wheel, a universal joint for supporting the jack from said member, actuating means for 20 the jack including a pattern shaft and cam and follower connections therefrom including connections operable to rotate said wheel in one direction to turn the jack to transfer the operation entirely around the shoe, and thereafter to 25 return the wheel in the opposite direction to the starting position, a latch on the rotatable jack supporting member arranged for movement between an operative position in latching engagement with said wheel to an alternative inoperative position in engagement with the relatively 30 stationary jack supporting arm, and means actuated by movement of the jack about said universal joint outwardly from the operating mechanism 35 to trip the latch to the inoperative position.

5. In an automatic machine for operating upon shoes, means for operating along the sole margin of the shoe, a shoe supporting jack, a system of supporting levers on which the jack is mounted for turning, tipping and feeding movements, a 40 pivotal supporting assembly connecting the jack with said system of levers including a jack rotating wheel, a rotatable jack supporting member concentric therewith, a universal joint connecting said member and the jack, jack operating means 45 including means for rotating the wheel to impart turning movements to the jack during the transfer of the operation completely around the sole margin of the shoe, and movable thereafter in a return direction to the starting position, means 50 operative upon completion of the operation to disengage the shoe from the operating means and to swing the jack outwardly on its pivotal support, a latch normally connecting the jack supporting member with the wheel, and means actuated by outward movement of the jack to disengage the latch to permit the return of said 55 wheel to starting position independently of the jack.

6. In an automatic machine for operating upon 60 shoes having means for operating along the sole margin of a shoe, the combination of a shoe supporting jack, jack supporting means including a jack supporting member and actuating means adapted for imparting turning, tipping and feeding 65 movements to the jack, means to transfer the operation entirely around the sole margin of the shoe, and thereafter to move the jacked shoe away from the operating means including a rotatable driving element for imparting turning 70 movements to the jack on said jack supporting 75 movements to the jack on said jack supporting

member, means for rotating said driving element from a starting position to transfer the operation about the shoe, and thereafter to return said driving element in a reverse direction to the starting position, a latch supported to turn with the jack shiftable between an operative position in latching relation with said rotatable driving element and a locking position in engagement with said jack supporting member, said latch being arranged with relation to the jack to be tripped from the operating to the locking position by the outward movement of the jack away from the shoe operating mechanism.

7. In a machine for operating upon shoes, having means for operating along the sole margin of the shoe, the combination of a shoe supporting jack having a rotary spindle, a supporting structure on which the jack spindle is mounted to turn including a jack supporting arm, a wheel rotatable on the arm, a rotatable spindle support concentric with the wheel, and connecting means shiftable to connect the rotatable spindle support in a fixed angular position to the jack supporting arm, and shiftable alternatively to connect the spindle support to turn with the wheel.

8. In a machine for operating upon shoes, having means for operating along the sole margin of the shoe, the combination of a shoe supporting jack having a rotary spindle, a supporting structure on which the jack spindle is mounted to turn including a jack supporting arm, a wheel rotatable on the arm, a rotatable spindle support concentric with the wheel, a locking recess in each of the supporting arm and wheel, and a latch on the spindle support shiftable to one position in locking engagement with the recess in the supporting arm and to an alternative position in locking engagement with the recess in the wheel.

9. In a machine for operating upon shoes, having means for operating along the sole margin of a shoe, the combination of a shoe supporting jack, a rotary spindle on which the jack is carried, a supporting structure on which the jack spindle is mounted for swinging movement about a plurality of axes, said structure including a horizontally disposed jack supporting arm, a wheel rotatable on the arm, a rotatable spindle support concentric with the wheel, a swivel connection between the spindle and spindle support, a locking recess in each of the supporting arm and wheel, a latch on the spindle support shiftable to one position in locking engagement with the recess in the supporting arm and to an alternative position in locking engagement with the recess in the wheel, and a trip member on the supporting arm arranged for one angular position of the rotatable spindle support and latch relative to the supporting arm to be actuated by outward movement of the jack spindle to trip the latch into engagement with the locking recess on the supporting arm.

10. In a machine for operating upon shoes having means for operating along the sole margin of the shoe, the combination of a shoe supporting jack having a rotary spindle, a supporting structure on which the jack spindle is mounted to turn including a jack supporting arm, a wheel rotatable on the arm, a rotatable spindle support concentric with the wheel, an annular rest surface formed on the wheel with a radially disposed locking recess formed therein, a locking recess in the supporting arm, a latch on the spindle support having a portion thereof disposed for engagement with said annular rest surface and for locking engagement with said radially disposed

recess, said latch having a second portion thereof disposed to be moved into locking engagement with the recess in the supporting arm for the disengaged position of said first-mentioned portion out of its recess upon the annular surface, spring means tending to move the latch against said annular surface of the wheel, and a trip member on the arm support arranged for one angular position of the rotatable spindle support and latch relative to the supporting arm to be actuated by outward movement of the jack spindle to trip the latch into engagement with the locking recess on the supporting arm.

11. In a machine for operating upon shoes, means for operating along the sole margin of the shoe, a shoe supporting jack having a rotary spindle, a supporting structure on which the jack spindle is mounted for swinging movement about a plurality of axes, said structure including a horizontally disposed jack supporting arm, a swivel connection between the spindle and arm comprising a ring bearing on the arm, a wheel mounted thereon, a ring support rotatably mounted on the wheel, pairs of pivot pins arranged on intersecting axes connecting the ring support with the spindle, and a latch carried on the ring support for locking engagement alternatively with the wheel and said jack supporting arm.

12. In a machine for operating upon shoes, means for operating along the sole margin of the shoe, a shoe supporting jack, supporting and actuating means adapted for imparting turning, tipping and feeding movements to the jack, a jack supporting and rotating assembly comprising a jack supporting arm, a wheel rotatably supported on the arm, a ring supporting member mounted concentrically with said wheel to turn relatively thereto, a universal joint for supporting the jack from said member, means for rotating the wheel from a starting position in one direction to turn the jack through a full revolution to transfer the operation entirely around the sole margin of the shoe and in the reverse direction to return said wheel to the starting position, a device operable for connecting the jack to the wheel for a single predetermined relative angular position only of the jack and wheel, and means for actuating said device to disconnect the jack while said wheel is moved in the reverse direction to the starting position.

13. In a machine for operating upon shoes having means for operating along the sole margin of the shoe, the combination of a shoe supporting jack, supporting and actuating means for the jack to present the jacked shoe to the operating means and to transfer the operation about the shoe, a pattern cam shaft arranged to be turned through a predetermined angular distance for the performance of an operation about the shoe, cams on the cam shaft selectively operable to transfer the operation about a portion only of the shoe and alternatively about the entire sole margin of a shoe, driving means for the machine including driving connections for rotating the cam shaft, and means in said driving connections to drive the cam shaft at alternative rates in accordance with the selection of said cams.

14. In a machine for operating upon shoes, means for operating along the sole margin of a shoe, a shoe supporting jack, supporting and actuating means for the jack including a pattern shaft and connections therefrom for moving the jack to present the shoe to the operating means

and to transfer the operation about the sole margin of the shoe, driving connections for driving the shoe operating means and pattern shaft in timed relation including a variable speed drive device for said jack adjusted in accordance with the size of shoe being operated upon to advance the point of operation about the shoe sole at a feed rate related to the rate of operation of the shoe operating means, and means for adjusting the machine for operation to transfer the point of operation from the breast line of the heel to the fore part of the shoe only, and alternatively to transfer the operation entirely around the sole margin of a shoe including the heel seat, and a change speed device for varying the rate of drive of said pattern shaft shiftable in accordance with said alternative adjustment for transfer of the operation about the shoe to maintain substantially unchanged the relation of the rate of jack feed to the rate of drive of said means for operating along the sole margin of the shoe.

15. In a machine for operating upon shoes, means for operating along the sole margin of the shoe, a shoe supporting jack, supporting and actuating means for the jack adapted for imparting tipping, turning and feeding movements to the jack to present the jacked shoe to the operating means and to transfer the operation about the shoe including a pattern cam shaft, cams on the pattern cam shaft operable during a revolution thereof to transfer the operation about the forepart only of the shoe from the breast line of the heel, alternatively selectable cams on the pattern cam shaft adapted for transferring the operation entirely around the sole margin of the shoe including the heel seat during one revolution of the pattern cam shaft, and driving mechanism for the machine for driving the shoe operating means and the pattern cam shaft in timed relation thereto including a change speed device to drive the pattern cam shaft at alternative rates in accordance with the selection of said cams to maintain substantially constant the relation of the rate of jack feed to the rate of drive of said means for operating along the sole margin of the shoe.

16. In a machine for operating upon shoes, means for operating along the sole margin of a shoe, a shoe supporting jack, supporting and actuating means for the jack for imparting tipping, turning and feeding movements to the jack to transfer the operation about the shoe including a pattern cam shaft arranged to be turned through a predetermined angular distance for the performance of an operation about the shoe, selectively operable cams on the pattern cam shaft for actuating the jack to transfer the operation about the sole margin of the shoe from the breast line of the heel about the forepart of the shoe only, and alternatively to transfer the operation entirely about the sole margin of the shoe including the heel seat while the cam shaft is turned through said predetermined angular distance, and a driving mechanism for driving said shoe operating means and pattern cam shaft including a change speed device operable for varying the rate of drive of the pattern cam shaft relative to the drive of said shoe operating means in accordance with the selection of said cams to maintain constant the relation of the rate of jack feed to the rate of drive of said means for operating along the sole margin of the shoe.

17. In a machine for operating upon shoes, means for operating along the sole margin of the shoe, a shoe supporting jack, supporting and ac-

tuating means for the jack including a pattern mechanism for imparting turning, tipping and feeding movements to the jack to present the shoe to the operating means and to transfer the operation about the sole margin of the shoe, driving connections for driving the shoe operating means and jack actuating means in timed relation to advance the point of operation about the shoe sole, means for adjusting said pattern mechanism for operation to transfer the point of operation from the breast line of the heel about the forepart of the shoe only and, alternatively, to transfer the operation entirely around the sole margin of a shoe including the heel seat, and means for varying the rate of drive of said jack actuating means to maintain substantially unchanged the relation of the rate of jack feed to the rate of drive of said means for operating along the sole margin of the shoe.

20. In a machine for operating upon shoes, means for operating along the sole margin of the shoe, a shoe supporting jack, supporting and actuating means for the jack including a pattern mechanism for imparting turning, tipping and feeding movements to the jack to present the shoe to the operating means and to transfer the operation about the sole margin of the shoe, driving and stopping mechanism for the machine, operating connections for driving the shoe operating means and jack actuating means in timed relation including a variable speed drive device for said jack adjusted in accordance with the size of shoe being operated upon to advance the point of operation about the shoe sole at a feed rate related to the rate of operation of the shoe operating means, and means for adjusting said pattern mechanism for operation to transfer the point of operation from the breastline of the heel about the forepart of the shoe only and, alternatively, to transfer the operation entirely around the sole margin of the shoe including a change speed device operable to drive the pattern mechanism alternatively at two different rates with relation to the shoe operating means to maintain substantially unchanged the relation of the feed rate of the shoe to the rate of drive of the means for operating along the sole margin of the shoe.

19. In a machine for operating upon shoes having means for operating along the sole margin of the shoe, the combination of a shoe supporting jack, a system of supporting levers on which the jack is mounted for turning, tipping and feeding movements, a jack rotating wheel arranged to be rotated in one direction to turn the jack to transfer the operation about the sole margin of the shoe and to be returned in the opposite direction to its starting position, a connecting device shiftable to an operative position connecting the jack to rotate with the wheel and to an alternative disengaged jack locking position in which the jack is locked against rotational movement during the return movement of the jack rotating wheel to the starting position, jack actuating means including a pattern cam shaft arranged to be turned through a predetermined angular distance for the performance of an operation about the shoe, cams on the cam shaft selectively operable to transfer the operation about a portion only of the shoe, and alternatively about the entire sole margin of a shoe, means operative only when the operation has been transferred entirely about the sole margin of the shoe to shift said connecting device to the disengaged locking position, driving means for

the machine including driving connections for rotating the cam shaft, and means in said driving connections to drive the cam shaft at alternative rates in accordance with the selection of said cams.

20. In an automatic machine for operating upon shoes, means for operating along the sole margin of the shoe, a shoe supporting jack, supporting means for the jack including a jack rotating wheel on which the jack is rotatably mounted, a latching device shiftable between a latching position in which the jack is connected to turn with the wheel and an alternative disconnected position, actuating means for the jack comprising a pattern cam shaft arranged to be turned through a predetermined angular distance for the performance of an operation about the shoe, alternatively operable groups of cams on the cam shaft for rotating said wheel and for moving the jack to transfer the operation about the sole margin of the shoe, one of said groups of cams being arranged to transfer the operation about the forepart only of the shoe and thereafter to return the wheel in the reverse direction to the starting position, and an alternative group of said cams being arranged for moving the jack to transfer the operation entirely about the sole margin of the shoe and thereafter to rotate the wheel in the reverse direction to starting position, means for rendering said groups of cams alternatively operable, driving connections for rotating the cam shaft, means in said driving connections to drive the shaft at alternative rates in accordance with the selection of said cam groups, and means operative when the jack has been turned to transfer the operation entirely about the shoe to disconnect the jack from the wheel for the reverse movement of the wheel to starting position.

21. In a machine for operating upon shoes, means for operating upon the sole margin of the shoe, a shoe supporting jack, supporting and actuating means for the jack comprising a pattern cam shaft, cams, and connections therefrom constructed and arranged to be rendered operative by rotation of the pattern cam shaft from an initial starting position through a revolution to impart tipping, turning and feeding movements to the jack to present the jacked shoe to the operating means and to transfer the point of operation entirely around the sole margin of the shoe, said cams acting thereafter to return the connections to the initial starting position, means operative upon completion of the transfer operation about the shoe to disconnect the jack from turning movement with said connections during the return of the connections to the initial position, and driving means adapted for driving said shoe operating means and cam shaft in timed relation.

lution to impart tipping, turning and feeding movements to the jack to present the jacked shoe to the operating means and to transfer the point of operation entirely around the sole margin of the shoe, said cams acting thereafter to return the connections to the initial starting position, means operative upon completion of the transfer operation about the shoe to disconnect the jack from turning movement with said connections during the return of the connections to the initial position, and driving means adapted for driving said shoe operating means and cam shaft in timed relation.

22. In an automatic machine for operating upon 15 shoes, means for operating along the sole margin of the shoe, a shoe supporting jack, supporting and actuating means for the jack comprising a pattern cam shaft, cams, and connections therefrom including a jack rotating wheel rendered operative by rotation of the pattern cam shaft from an initial starting position through substantially one revolution to impart tipping and feeding movements to the jack and to rotate said wheel and jack therewith to present the 20 jacked shoe to the operating means and to transfer the point of operation from a starting position entirely around the sole margin of the shoe, said cams acting thereafter to return said connections and to rotate said wheel in the reverse direction to the starting position, and means to disconnect the jack from the wheel to cause the wheel to be rotated independently of the jack to the starting position.
